UNITED STATES PATENT OFFICE.

JOSEPH G. GROFF, OF CONNERSVILLE, INDIANA.

SAW-GUARD.

SPECIFICATION forming part of Letters Patent No. 291,187, dated January 1, 1884.

Application filed October 15, 1883. (No model.)

To all whom it may concern:

Be it known that I, JOSEPH G. GROFF, of Connersville, in the county of Fayette and State of Indiana, have invented certain new and useful Improvements in Guards for Circular Saws; and I do hereby declare the following to be a full, clear, and exact description of the same, reference being had to the accompanying drawings, forming part of this specification, and to the figures and letters of reference marked thereon.

This invention relates to that class of saw-guards in which the hood normally rests upon the saw-table or near to it, rises automatically upon the approach of the board to be sawed, bears upon the board while being sawed, and drops back to normal position after the board has passed the saw.

The particular improvements which form the subject of the present patent will be understood from the following specification and claims, taken in connection with accompanying drawings.

Referring to said drawings, Figure 1 represents a side elevation of a saw-guard embodying my improvements, the saw-table being shown in section. Fig. 2 is a sectional view taken on the line $x-x$ of Fig. 1, and Fig. 3 is an enlarged view of a portion of the hood-frame and its connection.

Similar letters of reference in the several figures denote the same parts.

The hood proper consists of an arched metal portion, A, having the removable sides B attached by screws or otherwise, as shown. An upwardly-inclined projection, C, is formed upon or secured to the forward portion of the part A, while rearwardly-extending arms D D' are formed upon or secured to said part A at the rear thereof, as shown in Fig. 1. The said rearwardly-projecting arms D D' embrace a vertical plate, F, and are connected at their rear extremities by a cross bolt or screw, Z. The plate F is formed with a backwardly-inclined shank, which fits within a corresponding socket, G, secured to the saw-table, and its upper part passes up between the arms D D', and extends forward and partially over the hood, the latter being slotted, as shown by the dotted line, to receive it. The plate is provided with a long vertical slot, or preferably

with two vertical slots, S S', separated by a solid portion, I, and in these slots rollers q q', mounted in the arms D D', respectively, are adapted to work. The construction of these rollers and the manner of mounting them are best illustrated in Figs. 2 and 3—that is to say, each roller is provided with a peripheral groove to receive the edges of the plate F, and is secured by means of a screw-bolt, f, passing through the arms D or D', as the case may be, and through said roller. One end of the screw-bolt has a milled head, e, and the other end provided with a screw-nut, e'. The apertures in the upper arms, D, are round, while those in the lower arms, D', (marked g,) are oblong and extend horizontally, as shown clearly in Figs. 1 and 3. Each roller is also preferably provided with a hub, d, of a smaller diameter on each side, which hub projects within the opening through the arms D or D', as the case may be. Instead of the hubs, small rollers may be arranged upon the bolts with the same results. The upper portions of the slots S S' are enlarged, as shown in Fig. 1, to enable the rollers to be inserted in said slots. In front of the slots S S' the plate F is provided with another slot, S², in which is arranged a clamping set-screw, T, the office of which is to regulate the normal height of the hood with respect to the saw-table. The sides of the hood at the bottom are formed into inclines v and w, and are re-enforced by a rod of metal, m, to give additional strength, and pivoted to the projection C, at the forward end of the hood, 85 is a serrated or toothed dog, E, which is pushed up out of the way when the material to be sawed is advancing, but automatically resists any backward movement of the material by catching into the same. In Fig. 1 the hood and connected parts are shown in their normal position of rest. Upon the advance of the board to be sawed, the forward end of the board, striking against the upturned projection C, causes the hood to turn on the upper bolt, f, as a pivot, the horizontal slot g permitting this movement. Then, as the board further advances, its forward end strikes the incline v and raises the rear end of the hood, and causes the rollers q q' to travel up the vertical slots S S', as will be readily understood.

While the board is being acted upon by the

saw any tendency to a backward movement is resisted by the dog E, and as the board passes from under the hood its rear end, passing along the inclines *w v*, allows the hood to again resume its normal position, as will be understood.

Having thus described my invention, I claim as new—

1. The plate having the vertical slots, the hood having the rearwardly-extended arms embracing the plate, the lower arms having the horizontal slots, in combination with the rollers carried by said arms and working in the slots of the plate, substantially as described.

2. The combination of the plate having the two vertical slots for the rollers, and the third slot for the adjusting set-screw, with the hood having the rearwardly-extending arms provided with the horizontal slots, the rollers carried by said arms, and the adjusting set-screw, substantially as described.

INVENTOR, JOSEPH G. GROFF.
